ENGINE FRAME

Allison L. Bayles, Larchmont, N. Y.

Application September 2, 1944, Serial No. 552,514

8 Claims. (Cl. 123—195)

This invention relates to engine frames in general, and more specifically to cylinder unit or cylinder block constructions for opposed-piston internal combustion engines. The invention is applicable to all such engines, but will be described as applied to an engine of the class commonly called barrel type, axial, or round engines, the class having cylinders parallel to the shaft.

An object of the invention is to provide an improved cylinder unit for an opposed-piston engine, a unit which can be readily fabricated with little machine work and assembled by furnace-brazing. Another object is to provide an improved cylinder unit formed essentially as a double tube, the inner tube serving as the cylinder wall and the outer tube, in three separate lengths, serving as water jacket for the cylinder and as crosshead guides at both ends of the cylinder, the two tubes spaced by steel castings having the fins and ports, which would otherwise require much machining, cast in. Another object is to provide a cylinder block construction built up of the improved cylinder units.

These and other objects of the invention will be more apparent from the following description in connection with the drawing in which

Fig. 1 is a longitudinal section of an improved cylinder unit;

Fig. 2 is a side elevation, partly in section, of a cylinder block composed of seven cylinder units which may be arranged in a circle, the one shown in section having slightly different construction from that shown in Fig. 1;

Fig. 3 is an end view of the cylinder block shown in Fig. 2 and showing the circular arrangement;

Fig. 4 is a transverse section on the line 4—4 of Fig. 1; and

Fig. 5 is a transverse section on the line 5—5 of Fig. 1.

As shown in Figs. 1, 4, and 5, the cylinder unit consists essentially of a pair of tubes with cast collars separating them. Cylinder tube 10 having intake ports 11 and exhaust ports 12 (which may be punched into tube 10 rather than milled), has five cast steel collars pressed on its exterior, and outer tube 20 surrounds the collars and serves as water jacket wall for the length of cylinder tube 10 and as crosshead guides 13 at both ends of the cylinder. (With the starplate mechanism, it is desirable that the crosshead be of somewhat larger diameter than the piston.)

The central collar 14 has a boss for the injector and fins to provide more cooling area in the water jacket and faster flow of the coolant (since the fins restrict the passage), both to

remove heat more readily from the hotter central portion of the cylinder wall. Intake port collar 15 and exhaust port collar 16 are cast with radial ports and longitudinal water passages as shown, and need only be bored out to fit over the cylinder tube 10 and turned down on the outside to fit inside outer tube 20. Outer tube 20 may be in three lengths as shown, separated at the port zones to avoid machining any ports in tube 20. Then the whole assembly may be furnace-brazed into an integral structure, with copper or any other suitable welding alloy. Since all the fits involved are simple cylindrical fits, and all the machining can be punching and simple cylindrical boring and turning, there is no difficulty or expense in machining, and the joints formed in the furnace can be depended upon to be free from leaks and plenty strong.

After brazing, the unit is normalized to reduce the grain of the metal. Then the cylinder surface may be plated with chromium or otherwise prepared for service.

Any desired number of cylinder units may be assembled in any desired manner into a cylinder block or assembly. They may be bolted together, or clamped. Or they may be welded or brazed into a structure such as that shown in Fig. 2, in which case the normalizing and plating would be postponed until after assembly into the block.

The cylinder unit shown as part of Fig. 2 differs from that of Fig. 1 only that the inner tube 30 is cast integral with the three inner collars, after which the longitudinal water passages between the radial ports are drilled as indicated at 31, the exterior is turned down to fit into outer tube 20, and the end collars 32 are added to close the water jacket at the ends of the cylinder, the whole being pressed into outer tube 20, which may be in three lengths as in Fig. 1.

Seven such units are assembled in a series of central plates 40 and end plates 41, with intake passages 21 and exhaust manifold passages 22 arranged to close the water jackets from intake ports 11 and exhaust ports 12. Inner tube 42 supporting the inner main bearings of the shaft, closes the water jackets internally, fitting inside plates 40, and outer tubes 43 are wrapped around the exterior to close the water jackets outwardly and to provide surfaces on which to seal the manifolds or covers enclosing the whole. When the cylinder units have been properly assembled in the plates and other parts as shown, the whole block may be furnace-brazed or welded into an integral structure, after which it is normalized to reduce the grain of the steel, and the cylinder

surfaces may be plated with chromium or otherwise prepared for service.

Having thus described the invention, it is obvious that the objects of the invention as stated have been attained. While specific embodiments of the invention have been shown and described, it is understood that changes may be made in the construction or in the application of the invention without departing from the spirit or scope of the invention as expressed in the following claims.

I claim:

1. A cylinder block assembly for an opposed-piston internal combustion engine comprising a series of plates, holes similarly spaced in said plates, and a plurality of cylinder units fitting said holes, each of said cylinder units comprising an inner tubular member forming the cylinder wall and having intake ports toward one end and exhaust ports toward the other end thereof, an outer tube of larger diameter forming the cylinder water jacket for the length of said cylinder wall and the engine crosshead guides beyond each end of said cylinder wall, said outer tube in three lengths, one extending from said intake ports to said exhaust ports, another from said intake ports outward to one end of said unit, and the other from said exhaust ports outward to the other end of said unit, the several parts brazed together into an integral unit.

2. A cylinder block assembly for an opposed-piston internal combustion engine comprising a series of plates, holes similarly spaced in said plates, and a plurality of cylinder units fitting said holes, each of said cylinder units comprising an inner tubular member forming the cylinder wall and having intake ports toward one end and exhaust ports toward the other end thereof, an outer tube of larger diameter forming the cylinder water jacket for the length of said cylinder wall and the engine crosshead guides beyond each end of said cylinder wall, and a series of cast rings fitting outside said inner tube and inside said outer tube, one ring having fins providing more area for radiation of heat to the water, two rings one for said intake ports and one for said exhaust ports, each of said two rings having radial ports and longitudinal water passages between them, and a pair of end rings closing the water jacket at the ends of said cylinder wall, the several parts brazed together in an integral unit.

3. A cylinder block assembly for an opposed-piston internal combustion engine comprising a series of plates, holes similarly spaced in said plates, and a plurality of cylinder units fitting said holes, each of said cylinder units comprising an inner cast tubular member forming the cylinder wall and having intake ports toward one end and exhaust ports toward the other end thereof, an outer tube of larger diameter forming the cylinder water jacket for the length of said cylinder wall and the engine crosshead guides beyond the ends of said cylinder wall, said inner tubular member fitting inside said outer tube, and said outer tube in three lengths, one extending from said intake ports to said exhaust ports, another from said intake ports outward to one end of said unit, and the other from said exhaust ports to the other end of said unit, the several parts brazed together into an integral unit.

4. A cylinder block assembly for an opposed-piston internal combustion engine comprising a series of plates, holes similarly spaced in said

plates, and a plurality of cylinder units fitting said holes, each of said cylinder units comprising an inner tubular member forming the cylinder wall and having intake ports toward one end and exhaust ports toward the other end thereof, an outer tube of larger diameter forming the cylinder water jacket for the length of said cylinder wall and the engine crosshead guides beyond the ends of said cylinder wall, and a series of cast rings fitting outside said inner tube and inside said outer tube, one ring having fins providing more area for radiation of heat to the water, two rings one for said intake ports and the other for said exhaust ports, each of said two rings having radial ports and longitudinal water passages between them, and a pair of end rings closing the water jackets at the ends of said cylinder wall; said outer tube being in three lengths, one extending from said intake ports to said exhaust ports, another from said intake ports to one end of said unit, and the other from said exhaust ports to the other end of said unit, the several parts brazed together into an integral unit.

5. An engine cylinder unit comprising an inner tubular member forming the cylinder wall and having intake ports toward one end and exhaust ports toward the other end thereof, an outer tube of larger diameter forming the cylinder water jacket for the length of said cylinder wall and the engine crosshead guides beyond the ends of said cylinder wall, said outer tube in three lengths, one extending from said intake ports to said exhaust ports, another from said intake ports outward to one end of said unit, and the other from said exhaust ports outward to the other end of said unit, the several parts brazed together into an integral unit.

6. An engine cylinder unit comprising an inner tubular member forming the cylinder wall and having intake ports toward one end and exhaust ports toward the other end thereof, an outer tube of larger diameter forming the cylinder water jacket for the length of said cylinder wall and the engine crosshead guides beyond the ends of said cylinder wall, and a series of cast rings fitting outside said inner tube and inside said outer tube and closing the water jacket at the ends of said cylinder wall, the several parts brazed together into an integral unit.

7. An engine cylinder unit comprising an inner cast tubular member forming the cylinder wall and having intake ports toward one end and exhaust ports toward the other end thereof, an outer tube of larger diameter forming the cylinder water jacket for the length of said cylinder wall and the engine crosshead guides beyond the ends of said cylinder wall, said inner tubular member fitting inside said outer tube, and said outer tube in three lengths, one extending from said intake ports to said exhaust ports, another from said intake ports outward to one end of said unit, and the other from said exhaust ports to the other end of said unit, the several parts brazed together into an integral unit.

8. An engine cylinder unit comprising an inner tubular member forming the cylinder wall and having intake ports toward one end and exhaust ports toward the other end thereof, an outer tube of larger diameter forming the cylinder water jacket for the length of said cylinder wall and the engine crosshead guides beyond the ends of said cylinder wall, and a series of cast rings fitting outside said inner tube and inside said outer tube, one ring having fins pro-

viding more area for radiation of heat to the water in said jacket, two rings one for said intake ports and one for said exhaust ports, each of said two rings having radial ports and longitudinal water passages between them, and a pair of end rings closing the water jackets at the ends of said cylinder wall; said outer tube being in

three lengths, one extending from said intake ports to said exhaust ports, another from said intake ports to one end of said unit, and the other from said exhaust ports to the other end of said unit, the several parts brazed together into an integral unit.

ALLISON L. BAYLES.
